UNITED STATES PATENT OFFICE

ROBERT W. McLAUGHLIN, OF NEW YORK, N. Y., ASSIGNOR TO WARREN TELECHRON COMPANY, A CORPORATION OF MAINE

DESIGN FOR A CLOCK CASE

Application filed October 26, 1931. Serial No. 41,527. Term of patent 14 years.

To all whom it may concern:

Be it known that I, ROBERT W. McLAUGHLIN, a citizen of the United States, residing at New York, in the county of New York, State of New York, have invented a new, original, and ornamental Design for a Clock Case, of which the following is a specification, reference being had to the accompanying drawing, forming a part thereof.

The figure is a front perspective view of a clock case showing my new design.

I claim:

The ornamental design for a clock case as shown.

In witness whereof, I have hereunto set my hand.

ROBERT W. McLAUGHLIN.
